TAIL CLAMP

Filed May 14, 1928

FIG. 1

INVENTOR
BY Robert C. Pauly
Brackett & Hyde
ATTORNEYS

UNITED STATES PATENT OFFICE

ROBERT C. PAULY, OF CINCINNATI, OHIO, ASSIGNOR TO THE AMERICAN LAUNDRY MACHINERY COMPANY, OF CINCINNATI, OHIO, A CORPORATION OF OHIO

TAIL CLAMP

Application filed May 14, 1928. Serial No. 277,514.

This invention relates to ironing machines and particularly to tail clamping mechanism therefor.

In the ironing or finishing of various articles in the laundry, such as shirts, it is important to hold the tail to the shirts tightly after the bosom has been stretched in the proper position in which it is to be ironed or pressed. Some of the devices of this sort are in the form of a flexible band, usually of metal, drawn across the bosom and held under tension by a suitable manipulating means, but little attention has been paid to the arrangement of these devices so that they do not get in the way of the operator and so that they do not become out of place, so to speak, requiring the attention of the operative picking them up from the floor and work table of the machine.

In view of the foregoing, the present invention relates to a tail clamping mechanism of the band type so mounted and controlled that it is always effective for clamping the shirt in clamping position and ready for use when in non-clamping position and is prevented from being moved to an inconvenient or inaccessible place. The invention also relates to mechanism for applying the tensioning means to the clamping band so that it has its maximum clamping effort when in clamping position but is reduced in tension when in the inoperative or thrown back position.

Other details of the invention will be brought out in the following description, drawings and claims.

In the drawings, Fig. 1 is a perspective view of a portion of a press provided with the invention; Fig. 2 is an enlarged detailed view of a portion of the board with the clamping device applied thereto; Fig. 3 is a similar view taken from the rear of the machine; and Fig. 4 is a detailed view of the connection of the band to the front operating lever.

In the embodiment shown in the drawings, 1 represents the main frame adapted to support a work board 2 and a stationary ironing bed 3 which, as shown, is for re-

ceiving a shirt and is provided at the neckband end with a suitable neckband support generally indicated at 4. Cooperating with this bed is a suitable heated head 5 substantially conforming to and co-extensive with the bed and provided with the usual neckband recess 6.

The tail clamping mechanism comprises a pair of spaced brackets 7 and 8 extending down from the underside of the tail end of the ironing bed 3. The front bracket 8 receives a shaft 9 provided with a handle lever 10 which, when the clamp is applied, extends along the front edge of the board toward the neckband end. It has a suitable handle portion 11 and beyond this a projection 12 provided with an opening for receiving the threaded shank 12^a of an eye 13. A suitable nut 14, engaging the shank 12^a, holds the eye in any adjusted position. The end of the shank may be peened over at 15 for preventing its removal. In like manner the bracket 7 is provided with a shaft 16 carrying a lever 17 similar to the lever 10 and in like manner provided with an eye similar to the eye 13. These two eyes 13 are suitably pinned to the front and rear clevises 18 carrying a clamping strap 19 preferably of thin spring metal which extends across the board and is adapted to be brought down in clamping position across the board by suitable mechanism to be described.

Secured to the inner ends of the two shafts 9 and 16 is a U-shaped lever 20, shown in side elevation in Figs. 2 and 3 and in perspective and in dotted lines in Fig. 1. When the clamp is applied this U-shaped lever extends upward, as shown in Fig. 1, and it is adapted to receive the tensioning means which is in the form of a spring 21 secured to the lever, as shown in Fig. 2, and extends toward the neckband end of the board where it is secured by an adjustable connection 22 to a bracket 23 secured to the underside of the bed by any suitable means such as the stud and nut arrangement indicated at 24.

The arrangement of the parts thus far described is such that when the clamp is swung toward operative position, the levers

100

10 and 17 extend toward the neckband end of the board and the U-shaped lever 20 extends normally to the axis of the spring 21 so that in this position it exerts its maximum tension effect upon this U-shaped lever and therefore upon the entire clamp, thus holding the article in firmly clamped position upon the board. When it is swung in clockwise direction, as shown in Figs. 2 and 10 3, so that levers 10 and 17 are substantially horizontal as shown in dotted lines in Fig. 2, the U-shaped lever member 20 projects downward and the spring is carried across and below the axis of the shaft sections 19, 15 as shown, thereby exerting a tendency to further turn the clamping device to the right or clockwise. Undue motion in this direction, however, is prevented by a stop arm 25 forming a part of the lever 17 and 20 adapted, when the clamp is thrown to the rear as shown in Fig. 2, to engage a rubber or other yielding bumper 26 carried by a cup 27 secured to the ironing bed. In this retracted position of the clamp the tension 25 spring 21 pulls the clamp clockwise in a direction just beyond the axis of the shafts 9 and 16 so that the clamp is locked out of operative position. Since the pull of the tension device is almost across the center of 30 the shafts 9 and 16, relatively little operator effort is required to move the clamp to and from locked position. In other words, when the operator applies the clamp he does so against a minimum of spring tension effect when moving it from the off position 35 and moves it into a position where the tension spring exerts its maximum effort in clamping the work upon the bed.

In operation, the user dresses the shirt 40 upon the board with the neckband held in the neckband clamp and dresses the front portions upon the board in the desired arrangement. He then swings the clamp from the dotted line position, shown in Fig. 45 2, to the full line position in that figure and the work will be firmly clamped upon the board. Thereafter, he may stretch the bosom portions under the clamp to remove any wrinkles or the like.

50 What I claim is:

1. In a machine of the class described, an ironing board, a tail clamp frame including side members and a shaft member, bearings for said shaft member arranged transverse 55 to, beneath and near the tail end of said board to permit the free end of the frame to swing to and from positions upon the surface, and beyond the end of the board, a yielding strap carried by the free ends of 60 the side frame members and adapted to extend across the board, means for creating a tension upon said frame in either of its two extreme positions, and means for manipulating said clamp to a position over the 65 board and to a position beyond the same.

2. A machine of the class described in claim 1 wherein the tail clamp frame comprises a pair of spaced aligned shafts with side frame arms extending out beyond and at the sides of the board, and a lever connecting the inner ends of said shafts and connected to said tension means. 70

3. A machine of the class described in claim 1 wherein the tail clamp frame comprises a pair of spaced aligned shafts with side frame arms extending out beyond and at the sides of the board, and a U-shaped lever connecting the inner ends of said shafts and connected to said tension means. 75

4. A machine of the class described in claim 1 wherein the tail clamp frame comprises a pair of spaced aligned shafts with side frame arms extending out beyond and at the sides of the board, a lever connecting the inner ends of said shafts and connected to said tension means, and a stop for arresting the frame in its off position. 80

5. A machine of the class described in claim 1 wherein the tail clamp frame comprises a pair of spaced aligned shafts with side frame arms extending out beyond and at the sides of the board, and a U-shaped lever connecting the inner ends of said shaft and extending upward, a stop for limiting the movement of said frame in the off 90 position, and a spring connected to the cross member of the U-shaped lever and extending downwardly across the axis of said shaft for holding said clamp in either of its two 95 positions.

In testimony whereof I hereby affix my 100 signature.

ROBERT C. PAULY.
